UNITED STATES PATENT OFFICE.

LOUIS F. BERTRAU, OF COLUMBUS, OHIO, ASSIGNOR TO THE CHAMPION KEROSENE-BURNER COMPANY, OF KENTON, OHIO, A CORPORATION OF OHIO.

HYDROCARBON BURNER AND FURNACE.

1,320,973.

Specification of Letters Patent.

Patented Nov. 4, 1919.

Application filed May 2, 1919. Serial No. 294,274.

To all whom it may concern:

Be it known that I, LOUIS F. BERTRAU, a citizen of the United States, residing at Columbus, in the county of Franklin and State of Ohio, have invented certain new and useful Improvements in Hydrocarbon Burners and Furnaces; and I hereby declare that the following is a full, clear, and exact description thereof, reference being had to the accompanying drawings, which form part of this specification.

This invention is a novel improvement in apparatus for burning kerosene and like fluid hydrocarbons.

15 The objects of the invention are (1) to produce a simple, efficient and practical apparatus, which will reduce fluid hydrocarbons, such as kerosene, to a gaseous condition, and burn same in such manner that 20 all the fuel units in the kerosene will be utilized and there will practically be no odors, no smoke, and no waste of fuel. (2) To produce a kerosene burning apparatus that can be safely and readily operated by 25 non-skilled workmen and domestics. (3) To utilize such apparatus in a furnace for heating rivets and the like; and (4) to make an apparatus which requires but one valve to control the supply of fuel from the reservoir to the burner.

I will hereinafter refer to the apparatus as burning kerosene; using the word kerosene generically to include various fluid hydrocarbons like or akin to the ordinary so-called kerosene or "coal oil" such as is 35 commonly used in lamps, and in oil burning furnaces.

40 To enable others skilled in the art to fully understand and utilize the invention, and adapt the same to various purposes in the arts, I will describe the invention as applied to a furnace for heating rivets, as illustrated in the accompanying drawings, and the essentials of the invention, and novel combinations of parts and novel features of construction, for all of which I desire protection, are summarized in the claims.

45 The kerosene is preferably supplied under air pressure to my gas generating and burning apparatus to insure a practically continuous and uniform supply thereof; and such apparatus produces an intense non-oxidizing heat rendering such apparatus particularly useful in connection with heat-

ing and cooking stoves for dwellings; also 55 in furnaces, kilns and ovens in factories; and in furnaces for heating rivets, and the like; for the flame being free from oxidizing gases the rivets, for example, can be left in the furnace for an indefinite time without 60 being overburned or oxidized.

In the accompanying drawings:

Figure 1 is a front elevation of a complete kerosene burning rivet heating furnace embodying the novel features of the invention.

Fig. 2 is a side view of Fig. 1.

Fig. 3 is an enlarged vertical section on the line 3—3, Fig. 2.

Fig. 4 is a top plan view of the generator 70 and burner.

Fig. 5 is an end elevation of Fig. 4.

Fig. 6 is an enlarged transverse sectional view on line 6—6, Fig. 4.

Fig. 7 is a greatly enlarged sectional view 75 of the gas jet head.

The kerosene gas generator and burner, forming an essential feature of this invention, comprises a U-shaped retort 1, which may be made out of gas-pipe, detachably attached to and supported upon the exterior of an elongated hollow casting 2, the interior of which casting forms what I term a back-pressure gas-chamber C; which chamber is closed on all sides except for an inlet opening 2^a in its upper side near one end thereof, which is connected with the gas mixing tube 4 hereinafter referred to.

The casting 2 may be rectangular in cross section, and is preferably arranged in a horizontal position, and is shown as having a hollow or U-shaped flange 2^b projecting from its base. This flange preferably extends entirely around the casting and is adapted to be filled with a priming fuel, such as alcohol to initially start the burner.

The retort 1 may be connected with and supported on the exterior of the casting 2 in any suitable manner, and is shown as fastened to said casting by retainer straps 1^a secured to the casting by screws 1^b whereby the retort is supported at a proper distance above the flange 2^b; and said retort may be slightly spaced from the walls of the casting by any suitable means, as by vertical flanges or ribs 2^c formed on the outer walls of the casting.

In the side and inner end walls of the

casting 2 adjacent the retort 1, and in close proximity thereto are formed numerous closely adjacent minute perforations 2^e, as shown in Figs. 3 and 6, through which perforations gases escape from the back pressure gas chamber C and are burned to heat the retort as hereinafter explained.

One end of the retort 1 is connected by a reducing elbow 1^c, to the upper end of a vertically disposed reservoir or feeder 1^d, which may be formed of ordinary gas pipe, and which is connected with one end of a T 1^e, to the stem of which is connected the outlet end of a valve casing 1^f containing a needle valve operable by a handle 1^g, and to the inlet of said needle valve casing is connected a pipe 1^h leading to a suitable kerosene supply, such as a tank 7; hereinafter explained. A drain petcock 1ⁱ may be connected to the lower end of T 1^e, so that the retort 1 and feeder pipe 1^d may be drained when desired.

The other end of the retort 1 is connected by a reducing elbow 1^j with one end of a short pipe 1^k, the upper end of which is connected to a small T 1^l (shown greatly magnified in Fig. 7) which is preferably disposed in a horizontal plane and is closed at its outer end by a plug 1^m, and its inner end is closed by a removable jet head 1ⁿ. This jet head 1ⁿ is provided with a central jet aperture 1°, which is very minute and preferably cylindric and uniform in contour, so that the hot gases generated from the kerosene in the retort will escape in a small but forcible jet through the aperture 1° into the adjacent open end of a mixing tube 4, which may be formed of gas pipe, and is shown as supported in a horizontal position upon and above the casting 2 and directly opposite and in line with the aperture 1° in the jet head.

As shown the mixing tube 4 may be provided, at a point suitably removed from the jet head, with a T 4^a; the stem of which is connected with the upper end of a short pipe section 4^b, the lower end of which section is securely fitted to and engaged with the inlet opening 2^a of the back-pressure chamber C. This section 4^b serves both to (1) support the mixing tube 4 rigidly above and upon the casting 2, and also (2) as a means of communication between the mixing tube and the back-pressure chamber C. The discharge end of the mixing tube 4 is connected to the member or members to which the inflammable gaseous mixture formed in the mixing tube is to be delivered. In the example shown the discharge end of the mixing tube 4 is connected by an elbow 4^c to a downwardly extending pipe 4^d, which conducts the gaseous mixture into the heating chamber F of a rivet heating furnace 5, hereinafter explained, upon the top of which the generator and burner is supported.

I preferably provide a housing plate 2ⁿ, placed on top of the casting 2 and projecting beyond the edges thereof approximately as far as the flange 2^b projects, and the edges of this plate are curved downwardly at the sides and inner end of the casting toward the sides and end of the U-shaped retort 1, and it will be seen from Figs. 3 and 6 that the down turned sides and end of the plate 2ⁿ tend to confine the flames from the priming burner or flange 2^b, and from the jets 2^e, in close relation to the retort 1 and concentrate the heat from such flames upon said retort. The housing plate 2ⁿ may be provided with an opening 2° to permit the plate 2ⁿ to be readily placed on top of the casting 2 after the nipple 4^b is connected therewith; and it may be detachably secured in position on the casting 2 by a screw 2^p.

The rivet heating furnace 5 may have exterior metal side walls 5^a; and a metal top plate 5^b. This top plate has an extension 5^c at one side upon which the casting 2 is partially supported, as shown, so that the discharge pipe 4^d from the mixing tube 4 can enter the furnace chamber F through openings in the top wall of the furnace as shown. This furnace is thickly lined interiorly with fire brick, as indicated at 5^e; the fire brick covering the ceiling, walls, sides 95 and bottom of the furnace; except for a door opening in the front to permit access to the furnace chamber. This opening may be closed by any suitable means; a gravitational door 5^f being shown slidably hung upon a rod 5^g supported on brackets 5^h attached to the end walls of the furnace as shown.

The pipe 4^d discharges gas downwardly into the top of the furnace chamber F; suitable openings being formed in the top plate 105 of the furnace and in the fire brick lining for the passage of the pipe 4^d, and said pipe may be surrounded within such openings with a packing 4ⁱ of suitable non-heat conducting material, such as asbestos, to lessen the heating of the pipe, which is also protected by the fact that the burning gases are non-oxidizing.

The furnace 5 is shown as provided with a metal base plate 5^a and supported upon the top plate 6 of a suitable metal stand, having angle-iron legs 6^a, stiffened by braces 6^b, 6^c, and ties 6^d. Upon the latter is mounted a tank 7 which is provided with a pressure air gage 7^a; and an air inlet valve 7^b adapted for connection with any suitable compressed air supply,—such as a hand pump, not shown, or the usual compressed air distributing system installed in the building in which the furnace is used. This tank 7 is 115 also provided with a fuel filling nipple 7^c; and with a fuel outlet pipe 7^d which preferably extends to the bottom of the tank and may be provided on its inner end with a suitable strainer, (not shown) and on its 130

outer end with a valve 7^e to the outlet of which valve the kerosene supply pipe 1^h is connected.

I have found that the amount of gas admitted into the back pressure gas chamber C from the mixing tube 4 should be in proportion to the diameter and capacity of the retort 1 and mixing tube 4; and to enable one size of back-pressure gas chamber casting 2 to be used in the construction of any one of a number of generators and burners of different heating capacities, I preferably provide interchangeable annular bushings 4^e which may be placed in the stem of the T 4^a and rest upon the upper end of the pipe section 4^b. Such interchangeable bushings 4^e are provided having bores of different diameters, so that a bushing having an opening of the proper diameter to permit the proper amount of gas to pass from the mixing tube 4 into the back-pressure chamber C, can be used according to the size and capacity of the generator and burner.

In the construction shown the walls of the furnace chamber F and particularly the bottom thereof, form a baffle for the out-rushing stream of the inflammable gaseous mixture and cause complete combustion thereof. In actual use the furnace can be maintained at a high uniform heat, and objects placed therein may be heated to the desired temperature; but the combustion is so perfect that the flame is non-oxidizable, and metal rivets, for example, placed in such furnace and heated to incandescence can be maintained at such temperature without oxidation.

Part of the gaseous mixture passes from the mixing tube 4 through the pipe 4^d into the back-pressure chamber C in the casting 2, and issuing through the jets 1^e are ignited and the resultant flames maintain the retort 1 at a sufficiently high temperature to thoroughly reduce the kerosene admitted therein to a gaseous condition, the gases escaping very forcibly therefrom through the minute aperture 1° in the jet head 1^e.

The kerosene is fed under pressure and uniformly to the reservoir pipe 1^d; the amount of the supply being regulated by the valve 1^g; and a very slight opening of this valve insures a sufficient supply of kerosene to the retort during the practical operation of the furnace.

The retort should not be over-flowed or over-supplied with kerosene. The pipe 1^d being arranged vertically forms an intermediate reservoir for kerosene between the valve and the retort sufficient to compensate for any fluctuation in supply, and the back-pressure of the gases in the retort operates upon the column of kerosene in this reservoir and helps to control the supply, and

although the gases in the retort are highly heated the reservoir 1^d remains cool.

In starting the apparatus the hollow flange or priming burner 2^b may be filled with alcohol, or other suitable inflammable oil or material, and ignited, and the resultant flame therefrom rapidly heats the retort until gases are generated therein sufficient to produce inflammable mixtures in the mixing tube 4, and supply gas to the jets 2^e to maintain the heat of the retort after the priming fluid has burned out.

The inlet valve 1^g should be opened slightly to let the reservoir 1^d fill the kerosene and a small quantity flow into the retort 1 wherein it is quickly reduced to a gaseous condition by the heat and as the gases cannot escape backward they pass from the retort 1 through the pipe 1^h and escape in a minute forcible jet through the aperture 1° in the jet head into the open end of the mixing tube 4; the jet of gas draws air into this tube with it, and the air gas mixing therein form a highly combustible mixture.

Part of this mixture passes into the back-pressure chamber C and escaping through the apertures 1^e is ignited by the burning priming fluid and assists in heating the retort, and thereafter maintains the heat of the retort after the priming fluid has burned out. The main body of the inflammable mixture passes on to the point of utilization. As shown in the drawings, it passes through the pipe 4^d into the furnace chamber F; wherein it is ignited and burns without smoke or odor.

It is essential that some means of baffling the gaseous mixture be provided, as I have found that if the pipe 4^d is turned so as to discharge directly into the open air without obstruction, the gaseous mixture will not burn but will dissipate, whereas if such gases are discharged into the chamber F, or baffled by being partially confined, or impeded against a baffling surface, they will burn freely and with intense heat, and the combustion will be complete.

When the gas generating and burning apparatus is used in connection with a cooking or heating stove, the gases issuing from the mixing tube 4 could be conducted to burner heads by bifurcated or branched pipes substantially as shown for example in patent to Rusteberg No. 1,273,277 of July 23, 1918.

I have found that the relative proportions of certain of the parts of the generator and burner are important for the successful practical operation thereof. In the apparatus illustrated in the drawings the reservoir pipe 1^d is about six inches in length between its connection with the needle valve and its connection to the elbow 1^c; and about one-fourth inch in internal diameter. The re-

4
tort 1 is about three-eighths inch in internal diameter. The pipe 1^c is about one-eighth inch in internal diameter; the aperture 1^e in the jet head 1^a about 67 B. and S. gage 5 straight bore; the gas mixing tube 4 about one and one-fourth inches in internal diameter and the discharge pipe 4^d could be of the same size. The nipple or pipe 4^b should either be of about eleven-sixteenths of an 10 inch in internal diameter; or if of larger diameter provided with a bushing or choke rink 4^e as shown having an opening about eleven-sixteenths of an inch in internal diameter. The heating chamber F in the furnace 15 is about twelve-by-nine-by-nine inches in size. The needle valve 1^f should be about 15 degrees point and one-eighth of an inch in diameter; and the jet apertures in the casting 2 should be about one-eighth inch in 20 diameter and drilled quite close together so as to provide numerous jet apertures, making an almost continuous sheet of flame. I preferably avoid the use of slits as the gases do not burn as well or uniformly issuing 25 through slits as through small jet openings.

With the proportions given the apparatus using ordinary kerosene after it is properly started will produce continuously sufficient gaseous mixture to maintain the entire furnace 30 at a high temperature, sufficient to soften and almost liquefy the fire brick in the bottom of the furnace chamber F and most directly exposed to the incoming gases from the pipe 4^d.

35 The proportions above given for the relative sizes of different parts of the apparatus I have found after many tests to be substantially basic; and generators and burners of different capacities and sizes may be successfully made, based upon the relative proportions of parts above given.

The rivet heating furnace shown is very simple and practical and is readily portable, and as it is light can be moved from one 45 place in a shop or factory to another, or from one floor of a building to another, without any special lifting apparatus; and by reason of this portability the furnace can be placed so that the heated rivets can be 50 easily thrown from the furnace directly to the riveters. Furthermore, rivets can be heated rapidly in this furnace and as the flame is non-oxidizing rivets, etc., will not be injured if left in the furnace for an unusual 55 length of time, or such length of time as would burn them in an ordinary furnace or heating forge. Such furnace is very economical in fuel and can be operated with a great deal less kerosene per hour than prior 60 types of oil burning rivet heating furnaces.

While the invention is shown adapted for a rivet heating furnace, I do not consider the invention limited to use in connection with such furnaces, and the kerosene gas 65 generating and burning apparatus can be

adapted for many other purposes in the arts where a constant intense heat is desired.

With a so-called "plumber's torch" the retort 1 can be heated sufficiently to generate gas and supply the jets 1^e as quickly as, or 70 even more quickly than, can be done by burning alcohol in the primary burner flange 2^b. Therefore I do not consider the invention restricted to the use of the primary burner flange 2^b. 75

What I claim is:

1. In a kerosene gas generating and burning apparatus, a casting having an internal back-pressure gas chamber, a series of closely adjacent apertures in its sides, a gas 80 inlet adjacent one end thereof, and an exterior projecting hollow priming burner flange on its lower side; a retort supported on the side of this casting above the priming burner flange; an air and gas mixing tube; 85 a short pipe section supporting the mixing tube on the casting and connecting the tube with the back pressure chamber, and a choke ring in said pipe-section; a supply pipe connected with said retort, a valve for regulating the flow of kerosene to the retort; a jet 90 head connected with the discharge end of the retort adapted to direct gas generated in the retort into the mixing tube; a housing plate on the said casting overlying the retort; and means to conduct the inflammable mixture from the gas mixing tube to the point of utilization. 95

2. In a kerosene gas generating and burning apparatus having the following parts 100 relatively the dimensions stated, a retort approximately three-eighths of an inch in diameter; a reservoir pipe approximately one-fourth of an inch in diameter connected with the inlet end of the retort; a supply pipe connected with said reservoir pipe; a valve for regulating the flow of kerosene from the supply pipe to the reservoir; and a jet head connected with the discharge end 105 of the retort having a jet aperture of approximately 67 B. and S. gage. 110

3. In a kerosene gas generating and burning apparatus having the following parts of relatively the dimensions stated, a U-shaped retort approximately three-eighths 115 of an inch in diameter; a reservoir pipe approximately one-fourth of an inch in diameter connected with the inlet end of the retort; a supply pipe connected with said reservoir pipe; a needle valve for regulating 120 the flow of kerosene from the supply pipe to the reservoir; a reduced pipe approximately one-eighth of an inch in diameter connected with the discharge end of the retort; and a jet head having an aperture of 125 approximately 67 B. and S. gage connected with the end of said reduced pipe.

4. In a kerosene gas generating and burning apparatus, a casting having an internal back pressure gas chamber, a series of 130

5 closely adjacent jet apertures in its sides, and a retort supported on the side of this casting adjacent the jet apertures; an air and gas mixing tube; a short pipe section connecting the mixing tube with the back pressure chamber; and a changeable choke ring in said tube.

5. In a kerosene gas generating and burning apparatus having the following parts 10 of relatively the dimensions stated, a back pressure gas chamber having a series of apertures in its sides; a retort approximately three-eighths of an inch in diameter; an air and gas mixing tube approximately one and 15 one-fourth inches in diameter; a supply pipe connected with the inlet end of the retort; a valve for regulating the supply of kerosene; a jet head connected with the discharge end of the retort, having an aperture approximately 67 B. and S. gage 20 adapted to direct a jet of gas generated in the retort into the mixing tube; a connection approximately eleven-sixteenths of an inch in diameter between the mixing tube 25 and the said chamber; and means to conduct the inflammable mixture from the gas mixing tube to the point of utilization.

6. In a kerosene gas generating and burning apparatus having the following parts of 30 relatively the dimensions stated, a back pressure gas chamber having a series of apertures in its sides; a retort approximately three-eighths of an inch in diameter; an air and gas mixing tube approximately 35 one and one-fourth inches in diameter; a reservoir pipe approximately one-fourth of an inch in diameter connected with the inlet end of the retort; a supply pipe connected with said reservoir, a valve for regulating 40 the flow of kerosene to the reservoir; a jet head having an aperture approximately 67 B. and S. gage connected with the discharge end of the retort and adapted to direct gas generated in the retort into the mixing tube; 45 a connection approximately eleven-sixteenths of an inch in diameter between the mixing tube and the said chamber; and means for conducting the inflammable mixture from the mixing tube to the point of 50 utilization.

7. In a kerosene gas generating and burning apparatus, a back pressure gas chamber having a series of apertures in its sides; a retort approximately three-eighths of an inch in diameter, an air and gas mixing tube approximately one and one-fourth inches in diameter; a vertically disposed reservoir pipe approximately one-fourth of an inch in diameter connected with the inlet end of 55 the retort; a supply pipe connected with said reservoir; a valve for regulating the supply of kerosene from the supply pipe to the reservoir; a pipe approximately one-eighth of an inch in diameter connected with 60 the discharge end of the retort; and a jet 65

head connected with the end of this pipe and having a jet aperture approximately 67 B. and S. gage adapted to direct gas generated in the retort into the air and gas mixing tube; a connection approximately 70 eleven-sixteenths of an inch in diameter between the mixing tube and the said chamber; and means for conducting the inflammable mixture from the gas mixing tube to the point of utilization.

8. A portable kerosene burning furnace having an interior heating chamber; a kerosene gas generator mounted upon said casting; means for directing the combustible mixture from said generator into the chamber; a portable stand upon which the furnace and generator are mounted; a tank on said stand, and a pipe for conducting kerosene under pressure from said tank to the generator.

9. In a kerosene gas generating and burning apparatus, an elongated casting whose interior forms an internal back-pressure gas chamber having a series of aligned closely adjacent jet apertures in its sides and a gas inlet in its top adjacent one end thereof; a retort supported on this casting adjacent the apertures; an air and gas mixing tube above and extending parallel with the casting; a short tube extending at right angles to the casting and tube and supporting the mixing tube on the casting and connecting it with the back-pressure chamber; means for supplying kerosene to said retort, a valve for regulating the supply of kerosene; a jet-head connected with the discharge end of the retort and adapted to direct gas generated in the retort into the mixing tube; and means connected with the discharge end of the mixing tube to conduct inflammable mixture to the point of utilization.

10. In a kerosene gas generating and burning apparatus, an elongated casting whose interior forms an internal back-pressure gas chamber having a series of aligned closely adjacent jet apertures in its sides and a gas inlet in its top adjacent one end thereof; a retort adjacent the apertures; an air and gas mixing tube extending parallel with the casting; a short tube extending at right angles to the casting and tube and attaching the tube to the casting and connecting it with the back-pressure chamber; a reservoir pipe connected with the inlet end of the retort; a supply pipe connected with said reservoir pipe; a valve for regulating the supply of kerosene; a jet-head connected with the discharge end of the retort adapted to direct generated gas into the mixing tube; and means connected with the discharge end of the mixing tube to conduct inflammable mixture to the point of utilization.

11. In a kerosene gas generating and burning apparatus, an elongated casting

75

whose interior forms an internal back-pressure gas chamber having a series of alined closely adjacent jet apertures in its sides and a gas inlet in its top adjacent one end 5 thereof; a retort supported on and partly surrounding this casting adjacent the apertures; an air and gas mixing tube above and extending parallel with the casting; a short tube extending at right angles to the casting 10 and tube and attaching the mixing tube to the casting and connecting it with the back-pressure chamber; a reservoir pipe connected with the inlet end of the retort; a supply pipe connected with said reservoir pipe; a valve 15 for regulating the supply of kerosene from the supply pipe to the reservoir; a reduced pipe connected with the discharge end of the retort; a jet-head connected with the end of this reduced pipe and adapted to 20 direct generated gas into the mixing tube; and means connected with the discharge end of the mixing tube to conduct the inflammable mixture to the point of utilization.

12. A kerosene gas generating and burning apparatus comprising an elongated hollow casting whose interior forms a back-pressure gas chamber having an alined series of closely adjacent gas apertures in its sides; a U-shaped pipe exterior 25 to and partly surrounding said casting opposite the gas apertures therein; a horizontally disposed air and gas mixing tube above the casting; a tubular connection between this mixing tube near one end thereof 30 and the said chamber; a supply connected with one end of the U-shaped pipe; a valve for regulating the supply of kerosene to the pipe. a jet-head opposite the inlet end of the mixing tube adapted to direct gas generated 35 in the pipe into the mixing tube; a connection between the other end of the pipe and said jet-head; means for conducting the inflammable mixture from the gas mixing tube to the point of utilization; and an abutment 40 against which the inflammable mixture is discharged.

13. A kerosene gas generating and burning apparatus comprising a hollow horizontally disposed casting whose interior forms 45 a back-pressure gas chamber having a horizontally alined series of closely adjacent gas apertures in its sides and one end; a U-shaped retort exterior to and partly surrounding said casting and supported opposite the gas apertures therein; a horizontally 50 disposed air and gas mixing tube above the casting; a lateral connection between this tube near one end thereof and the said chamber; a kerosene supply connected with one 55 end of the U-shaped retort; a valve for regulating the supply of kerosene; a jet-head opposite the inlet end of the mixing tube, adapted to direct gas generated in the retort 60 into the air and gas mixing tube; a connection 65 between the other end of the retort and

said jet-head; means for conducting the inflammable mixture from the gas mixing tube to the point of utilization; and an abutment against which the inflammable mixture is discharged.

14. In a kerosene gas generating and burning apparatus, a single casting whose interior forms an internal back-pressure gas chamber, having a series of alined apertures in its sides, and a gas inlet adjacent one end; 70 a U-shaped retort partly surrounding the casting adjacent the apertures therein; a housing plate mounted on the said casting above and overlying the retort; an air and gas mixing tube laterally connected with 75 the gas inlet of the casting; a jet-head adapted to direct gas generated in the retort into the inlet end of the air and gas mixing tube; a kerosene supply connected with one end of the retort; a valve for regulating the 80 supply of kerosene; means for conducting gas from the other end of the retort to the jet-head; means for conducting the inflammable mixture from the mixing tube to the point of utilization; and an abutment against 85 which the inflammable mixture is discharged.

15. In a kerosene gas generating and burning apparatus, an elongated casting whose interior forms an internal back pressure gas chamber having a series of alined closely adjacent jet apertures in its sides, a gas inlet in its top adjacent one end thereof; a U-shaped retort supported on and partly surrounding this casting adjacent the apertures; an air and gas mixing tube above the casting; a short tube supporting the mixing tube on the casting and connecting it with the back-pressure chamber; a housing plate on the said casting above and overlying the 95 retort; a reservoir pipe connected with the inlet end of the retort; a supply pipe connected with said reservoir; a valve for regulating the flow of kerosene from the supply pipe to the reservoir; a reduced pipe connected with the discharge end of the retort; a jet-head connected with the end of this reduced pipe and adapted to direct gas generated in the retort into the air and gas mixing tube; and means connected with the discharge end of the mixing tube to conduct the inflammable mixture to the point of utilization.

16. In a kerosene gas generating and burning apparatus, a casting having an internal back-pressure gas chamber and a series of closely adjacent jet apertures in its sides; a retort at the side of this casting opposite the jet apertures; an air and gas-mixing tube mounted above the casting; a supply pipe connected with the inlet end of the retort; a valve for regulating the supply of kerosene to the retort; a jet-head connected with the discharge end of the retort adapted to direct a jet of gas generated in the retort 120 125 130

into the air and gas mixing tube; a removable housing plate mounted on the said casting and overlying the retort.

17. For kerosene gas generating and burning apparatus, an elongated casting having a back-pressure gas chamber in its interior, an alined series of closely adjacent jet apertures in its side walls and one end wall, a gas inlet in its top, and an exterior 10 priming burner flange projecting around its lower portion, all substantially as described.

18. In a kerosene gas generating and burning apparatus, a casting having an internal back-pressure gas chamber, and jet

apertures in its sides; a retort at the side of 15 this casting opposite the jet apertures; an air and gas mixing tube; a tubular connection between the mixing tube and said gas chamber; a removable check ring in this connection; a supply pipe connected with 20 the inlet of the retort; a valve for regulating the supply of kerosene; and means to direct the gas generated in the retort into the air and gas mixing tube, substantially as described.

In testimony that I claim the foregoing as my own, I affix my signature.

LOUIS F. BERTRAU.
